UNITED STATES PATENT OFFICE

106,892

DESIGN FOR A BOBBIN FOR LOOM SHUTTLES OR SIMILAR ARTICLES

William J. McGeough, Providence, R. I., assignor to U. S. Bobbin & Shuttle Company, Providence, R. I., a corporation of Rhode Island

Application November 13, 1936, Serial No. 65,892

Term of patent 14 years

To all whom it may concern:

Be it known that I, William J. McGeough, a citizen of the United States of America, residing at Providence, in the county of Providence and State of Rhode Island, have invented a new, original, and ornamental Design for Bobbins for Loom Shuttles or Similar Articles, of which the following is a specification, reference being had to the accompanying drawing, forming a part thereof.

Fig. 1 is a front elevation of a bobbin showing my new design; and

Fig. 2 is a side elevation thereof.

The dominant feature of this invention resides in a bobbin of tapering thickness substantially

unobstructed on its sides and edges from end to end and terminating at the thinner end in substantially a point and having at its thicker end a reduced oval shaped neck of short length and surrounded by spaced beads, the major diameter of the neck being such that the outer surfaces of the beads form substantially a continuation of and lie in substantially the same plane as the tapered edges of the bobbin.

I claim:

The ornamental design for a bobbin for loom shuttles or similar articles, substantially as shown and described.

WILLIAM J. McGEOUGH.
